UNITED STATES PATENT OFFICE.

FRANK O. ANDERSON, OF JAMESTOWN, NEW YORK.

DESIGN FOR A DRESSER.

No. 40,145.

Specification for Design.

Patented July 13, 1909.

Application filed January 8, 1909. Serial No. 471,371. Term of patent 7 years.

To all whom it may concern:

Be it known that I, FRANK O. ANDERSON, a citizen of the United States, residing at Jamestown, in the county of Chautauqua, State of New York, have invented a new, original, and ornamental Design for Dressers, of which the following is a specification, reference being had to the accompanying drawing, forming a part thereof.

The figure of the drawing is a perspective view showing the design of the dresser.

The plain top A has a narrow rounded edge

or bead *a* and between the rounded edge *a* and a corresponding edge *b* located a short distance below the same, the surface is in the form of an ogee molding B, with vertical divisions C at the front of the dresser.

I claim:

The ornamental design for a dresser, shown and described.

FRANK O. ANDERSON.
